CLOSURE OPERATOR

Chester A. Diller, Lancaster, Pa.

Application October 18, 1934, Serial No. 748,930

10 Claims. (Cl. 268—40)

This invention relates to closure operators and more particularly to mechanism for opening and closing garage doors.

Briefly, the invention consists in the provision of a mechanism whereby the doors of a garage may be opened in a somewhat automatic manner and without requiring the operator of the vehicle to leave his position in the vehicle when either entering or leaving the garage.

10 The present invention involves certain new and useful improvements over the garage door operating mechanism disclosed in Patent No. 1,961,283, granted to me on June 5, 1934, and entitled "Garage door operating mechanism".

15 The present invention, together with its objects and advantages, will be best understood from a study of the following description, taken in connection with the accompanying drawings, where-

in:

20 Figure 1 is a somewhat diagrammatic view with certain parts shown in plan and other parts in section, and illustrating the application of the invention.

25 Figure 2 is a detail sectional elevational view further illustrating the application of the invention.

Figure 3 is a view showing in longitudinal section front and rear tracks and blocks operating therein, as will be hereinafter more fully pointed out.

30 Figure 4 is a longitudinal sectional view through one of the track assemblies on an enlarged scale.

Figure 5 is a detail sectional view taken substantially on line 5—5 of Figure 4.

35 Figure 6 is a view somewhat similar to Figure 5 and taken at a point spaced relative to the section on which Figure 5 is taken.

Figure 7 is a perspective view of several blocks hereinafter more fully referred to.

40 Figure 8 is an enlarged detail side elevational view of a track assembly.

Figure 9 is a view showing in perspective front and rear track assemblies and manual operating mechanism associated therewith.

45 Figure 10 is a horizontal sectional view illustrating certain details of construction hereinafter more fully referred to.

Figure 11 is a fragmentary transverse sectional view through a portion of a track assembly illustrating certain details of the mechanism shown in Figure 9.

50 Figure 12 is an enlarged detail sectional view taken through the mechanism.

Figure 13 is a detail view taken substantially on the line 13—13 of Figure 18.

Figure 14 is an elevational view of the weight-equipped end of a trip lever.

Figure 15 is an elevational view of a clutch member.

Figure 16 is a diagrammatic view showing one 5 of the mechanisms associated with one door member for operating the latter.

Figure 17 is a bottom plan view of a carriage.

Figure 18 is a top plan view of the carriage.

Referring to the drawings in detail, it will be 10 seen that the reference numeral 1 designates generally a garage of conventional construction which is provided with a pair of sliding doors 2.

Extending longitudinally of the garage to a point somewhat in front of the garage is a sunken 15 runway designated generally by the reference numeral 3. The runway 3 is closed by a cover 4 having a longitudinal slot 5 therein. Operable in the runway 3 is a carriage 10 including a frame 11 which is mounted on supporting wheels 12. 20 Fixed transversely in the frame 11 is a polygonal shaft 13 having a bearing 6 at an intermediate point upon which the hub portion 15 of a trip lever 16 is journaled, said lever 16 being operable in the slot 5. The hub portion 15 diametrically opposite to the lever 16 is provided with a weight 7 which acts to normally retain the lever 16 in a vertical or perpendicular position. Slidably mounted on the shaft 13 are spring actuated clutches 17 which are operatively engageable with the opposite faces 30 of the hub portion 5 for releasably locking the lever 16 against swinging movement on the bearing 6. The hub portion 15 of the lever 16 is provided with radial grooves 18 (see Figure 14) for the reception of the teeth of the clutches. 35

Mounted longitudinally of the runway 3 at the outer end of the runway, and adjacent opposite sides of the runway is a pair of opposed, substantially shell-like, elongated tracks 19 and 20, while similar opposed tracks 19a and 20a are 40 mounted at the inner end of the runway 3 (see Figure 1).

Each of the tracks as best shown in Figures 3 and 4 includes an upper runway and a lower runway, the upper runway of the tracks 19 and 45 20 being designated by the reference numeral 21, and of the tracks 19a and 20a by the reference numeral 21a, while the lower runways of the tracks 19 and 20 are indicated by the reference numeral 22, and the lower runways of the tracks 50 19a and 20a are indicated by the reference numeral 22a. The tracks on corresponding sides of the runway 3 are connected by guides 34 as best shown in Figures 1 and 2.

Slidably mounted in the runways of the tracks 55

are pairs of blocks, the blocks of the pair operating in the runway 21 being indicated by the reference numerals 23 and 24 respectively and the blocks of the pair of blocks operating in the 5 runways 22 being indicated by the reference numerals 25 and 26, respectively. The blocks of the pairs of blocks operating in the runways 21a are indicated by the reference numerals 23a and 24a respectively while the blocks of the pairs of blocks operating in the runways 22a are indicated by the reference numerals 25a and 26a respectively (see Figure 3).

Engageable with the blocks 23, 25, 24a and 25a in a manner hereinafter more fully pointed out 15 are angular arms 27 which are vertically slidable in guides 28 provided on the frame 1 of the carriage 10. The upper ends of the arms 27 operate in the slots 29 and 30 provided on the confronting sides of the tracks 19 and 20, the slots 20 29a and 30a provided on the confronting sides of the tracks 19a and 20a, the entrance slots 31 provided at one end of the slots 29, the diagonal slots 32 and 33 connecting adjacent ends of the slots 29 and 30, the slots 34a in the guides 34 25 connecting the slots 30 with the slots 30a and the diagonal slots 32a and 33a connecting the adjacent ends of the slots 29a and 30a; the arrangement of slots being best shown in Figure 2.

The aforementioned blocks 24, 26, 23a and 26a 30 are grooved as at 35 to clear to the free ends of the arms 27 permitting the arms to move relative to the mentioned blocks and into engagement with the blocks 23, 25, 24a and 25a as will be understood from a consideration of Figures 35 3, 4 and 16.

For each door 2 there is provided an outer substantially triangular arrangement of sheaves 36, 37, and 38; and an inner similar arrangement of sheaves 36a, 37a, and 38a. The arrangement of the sheaves will be best seen in 40 Figure 1. In the plane of the hypotenuse of each triangular arrangement of sheaves is a suitably mounted rack bar, the rack bar for the first arrangement of sheaves 36, 37, and 38 being indicated by the reference numeral 39, and the rack bar for the second series of sheaves being indicated by the reference numeral 39a. The rack bars are provided at each end with a series of 45 rack teeth engageable, in the case of the bar 39, with rack wheels 40 fixed to the axes of the sheaves 37 and 38, and in the case of the rack bar 39a with ratchet wheels 40a fixed to the axes of the sheaves 37a and 38a.

Each triangular arrangement of sheaves further includes a door opening cable 41 which at 50 one end is secured as at 42 to the lower edge of a door 2 and which, at its opposite end, is secured, in the case of one of the cables 41, to the sheave 37 and is windable on the sheave, while in the case of the other of the cables 41 it is secured to the sheave 37a and is windable thereon. Also secured to a windable on the sheaves 55 38 and 38a are cables 43, of which the cable 43 associated with the sheave 38, is secured to one end of the block 23 while in the case of the cable 43 associated with the sheave 38a the said cable is secured at one end to the block 24a.

Each set of inner and outer pulleys or sheaves includes a third or door closing cable 44 secured 60 at one end to the door 2 as at 45, and in the case of the cable 44 of the outer set of sheaves, said cable is trained on the sheave 36 and secured to the block 25. The cable 44 associated with the inner series of sheaves is trained over sheave 36a and is secured to block 25a.

Secured at one end to each block 24 and extending through an opening 23b provided in the companion block 23 is a cable 46 trained over suitably mounted and located pulleys 47 and equipped at its free end with a weight 48. 5 A similar take-up cable 49 is secured at one end to each block 26, extends through an opening in companion block 25 corresponding to the opening in the block 23, is trained over a suitably arranged pulley 47' and is equipped at its free end with a weight 50. In this connection, it will also be understood that the blocks 23a and 26a 10 are provided with similarly arranged and weight-equipped cables as are the blocks 24 and 26.

For preventing, in a releasable manner, return movement of the blocks 23 and 24 operating in each upper run 21, said run at one end is provided with hinged run section 52, while for the same purpose with regard to the block 23a and 24a, each run 21a is provided at one end in a 20 similar manner with a hinged run section 52a. Likewise, at the end thereof farthest remote from the run section 52, each lower run 22 is provided with a hinged run section 53 and each lower run section 22a is similarly provided with a hinged 25 run section 53a. At the free ends of the run sections, each run is provided with a stop shoulder 54 as best shown in Figure 4.

For levelling the run sections with their respective runs, the frame 11 of carriage 10 is provided with opposed cams 55 that are cooperable with cam followers 56 and 56a respectively pivoted to the runs 53 and 53a respectively so as to swing in one direction only, and with cam followers 57 and 57a respectively associated with the 35 run sections 52 and 52a through the medium of frames 58 of the type shown and which are connected to the respective run sections 52 and 52a as best shown in Figure 5; cam followers 57 and 57a being respectively pivoted to their association frames 58 to swing only in one direction. 40

For simultaneously levelling the runways 52, 52a, 53 and 53a the aforementioned hinged runway sections are connected in pairs in a suitable manner through the medium of aligned links 45 68, 69 respectively, pivoted at adjacent end to swing in reverse direction as at 70, and at said pivoted end being arranged in overlapping relation and loosely connected together as at 71.

The operation and utility of the device will be 50 apparent from the following:

Assuming that the doors to the vehicle are closed and the vehicle entering the runway leading to the garage is moving forwardly to enter the garage. As the vehicle proceeds, the front bumper thereof will strike the upper end of the trip lever 16, and by reason of the clutches 17 engaged with the hub 15 of said lever to hold the lever against rocking movement, the carriage 10 will be caused to move forwardly toward the left in 60 Figure 2. As the carriage 10 moves forwardly in this manner, the arms 27 will engage the blocks 23 for unwinding the cables 43 and at the same time cause a clock-wise rotation of the pulley 38 which will through the medium of the rack bar 39 65 and the rack wheels 40 cause a rotation of the pulley 37 for winding the cable 41 thereon and causing the associated door 2 to slide to an open position.

Also, as the carriage moves inwardly it will be understood that cams 55 engaging the cam followers 56 will cause the runway sections 53 to 70 swing upwardly to a level position with the runways 22 and by reason of the connection between the runway sections all of said sections will move upwardly to a position level with their respective 75

runways releasing all of the blocks, permitting the blocks to move in a proper direction and thereby allow the door 2 to slide to open position.

At about the time the cams 55 move past the 5 cam followers 57 blocks 23 and 24 will have moved into position on the runway sections 52 which is now returned to its lowered position permitting the blocks 23 and 24 to engage behind the shoulder 54 and thereby secure the doors 2 in open position.

10 During the movement of the carriage between the ends of the trackways the arms 27 will operate in the slots 34a provided in the guides 34 so as to pass into the slots 30a as the vehicle continues its movement inwardly of the garage.

20 As the arms 27 move into the slots 30a said arms will engage the blocks 25a which at that time will be located at the forward end of the runway 22a. As the blocks 25a and 26a move toward the inner ends of the trackways 19a and 25 20a, being propelled by the arms 27 engaged with the carriage 10, and blocks 23a and 24a being released to move in a corresponding direction with the blocks 25a and 26a by reason of the engagement of the cams 55 with the cam followers 57a 30 and the consequent pivoting of the links 69 to elevate the runway 52a, the doors 2 will be caused to slide to a closed position behind the vehicle entering the garage. As the blocks 25a and 26a approach the inner ends of the runway 35 22a they will come to rest on the runway sections 53a which, after the cams 55 on the carriage pass beyond the cam followers 56a, will drop down to the position shown in Figure 3 so that the blocks 25a and 26a will engage behind the adjacent shoulder 54 and thereby releasably secure the doors 2 in closed position.

40 In connection with the above, it will be also noted that as the carriage 10 approaches either end of the runway 3 pins 60 depending from the 45 clutch member 17 will engage blocks 62 located at the bottom of the runway in a manner to cause the clutch member 17 to move laterally in reverse direction out of engagement with the hub 15 thereby freeing the lever 16 permitting the same to rotate sufficiently to allow the bumper of the 50 automobile to pass out of engagement with the lever.

55 For the purpose of re-engaging the clutch member 17 with the hub 15 of the lever 16 after a release of the automobile bumper and lever 16 there are located in the ends of the runway 3 springs S that act on the carriage 10 to project the latter inwardly beyond the inner end of the blocks 62, and obviously upon movement of the 60 carriage inwardly the pins 60 move out of engagement with the blocks 62 and the clutch member 17 move inwardly into engagement with the hub 15 of the lever to secure the lever in vertical up-standing position. Thus the parts are recessed 65 for the next door opening and closing operation.

70 For automatically opening the doors 2 to permit the automobile to move out of the garage the operations above described are reversed, initial movement of the carriage acting by reason of the engagement of the cams 55 with followers 56a to release the blocks 25a and 26a, and simultaneously with the release of blocks 25a and 26a the blocks 23 and 24 so that all the blocks are free to move to permit an opening of the doors 2 as the vehicle 75 is backed out of the garage.

As suggested in Figure 8 there is provided at the upper ends of the diagonal slots 32 and 32a pivoted top elements 68 which serve to close the upper ends of said slots upon passage of the lateral ends of the arms 27 from said slots into aligned slots 29 and 31 so as to prevent said arms 27 re-entering the slots 32 as the arms move to the extreme ends of the slots 31 as is required for disengagement of the lever 16 with the bumper of the automobile after the automobile has passed wholly out of the garage, and upon movement of the arms 27 toward the extreme end of the slot extension 31a as is necessary to effect a release of the lever 16 when the vehicle is wholly within the garage.

10 Means is also provided for manually elevating the runway sections 52, 52a, 53, and 53a to release the blocks when it is desired to manually open or close either or both of the doors. Such means for each door consists of an operating 20 cable 63 provided with an actuating ring 64 that normally rests on the outer surface of the runway cover 4. The cable 63 extends longitudinally of the runway 3, being trained over suitably arranged pulleys 65 and 66. The cable 63 is 25 suitably connected with pins 67 with which the runway sections adjacent their free ends are provided as shown in Figure 11 so that upon an upward pull of the ring 64 said sections will be swung upwardly into a position level with their respective or associated runways in a manner to free all of the blocks on one side of runway 3 to permit a sliding of the proper door 2 to an opened or closed position.

30 While I have herein illustrated the invention 35 as used for opening and closing garage doors, and as being operable by an automobile, it will be understood that the invention may be employed equally as well for opening and closing gates, and is capable of being operated by any suitable 40 automotive force.

Having thus described the invention what is claimed as new is:

1. A mechanism of the class described for operating garage doors comprising a runway, tracks 45 mounted in the runway, said tracks having upper and lower runs, blocks operating in said runs, a carriage operable in the runway, means carried by the carriage and engageable with the blocks for moving the latter along the runs of the tracks, 50 door opening mechanism, and operating connections between said mechanism and the blocks for opening and closing the doors incidental to a movement of the carriage along said runway.

2. A mechanism of the class described for operating garage doors comprising a runway, tracks 55 mounted in the runway, said tracks having upper and lower runs, blocks operating in said runs, a carriage operable in the runway, means carried by the carriage and engageable with the blocks 60 for moving the latter along the runs of the tracks, door opening mechanism, and operating connections between said mechanism and the blocks for opening and closing the doors incidental to a movement of the carriage along said runway, the 65 runs of said tracks having pivoted sections depressible by the weight of the blocks thereon, in a manner to releasably secure the blocks against movement for locking the doors in open and closed positions, and means controlled by the 70 movement of the carriage along the runway for swinging the track run sections upwardly to release said blocks and thereby permit a movement of the doors to either open or closed condition optionally.

3. A mechanism of the class described for operating garage doors comprising a runway, tracks mounted in the runway, said tracks having upper and lower runs, blocks operating in said runs, a carriage operable in the runway, means carried by the carriage and engageable with the blocks for moving the latter along the runs of the tracks, door opening mechanism, and operating connections between said mechanism and the blocks for opening and closing the door incidental to a movement of the carriage along said runway, the runs of said tracks having pivoted sections depressible by the weight of the blocks thereon in a manner to releasably secure the blocks against movement for locking the doors in open and closed position, and means controlled by the movement of the carriage along the runway for swinging the track run sections upwardly to release said blocks and thereby permit a movement of the doors to either open or closed position optionally, and means for operatively connecting the carriage to a passing vehicle for actuation thereby.

4. A mechanism of the class described for operating garage doors comprising a runway, tracks mounted in the runway, said tracks being provided with upper and lower runs having pivoted sections, blocks slideable in the runs of the tracks, garage door operating mechanism connected with the doors of the garage and located adjacent said runway, means operatively connecting said door operating mechanism with the blocks for actuating said mechanism to open and close the doors, means on the carriage engageable with the blocks for moving the latter along the tracks, the pivoted run sections being depressible by the weight of the blocks in a manner to retain the blocks, releasably, against movement to lock the doors in either open or closed position, means operatively connecting the pivoted run sections for simultaneous operation, and means on the carriage for actuating said last mentioned means to release the blocks to permit movement of the doors to open or closed position, and means for operatively connecting the carriage to a passing vehicle for actuation thereby, said last named means including clutch means for releasing the carriage when the latter has moved to either end of the runway.

5. A mechanism of the class described for operating garage doors comprising a runway, tracks mounted in the runway, said tracks having upper and lower runs, blocks operating in said runs, a carriage operable in the runway, means carried by the carriage and engageable with the blocks for moving the latter along the runs of the tracks, door opening mechanism, and operating connections between said mechanism and the blocks for opening and closing the doors incidental to a movement of the carriage along said runway, means within the runs of the tracks for engaging the blocks for holding the door in either of two positions, and manual means for simultaneously releasing the blocks to permit opening and closing of the doors independently of the carriage controlled mechanism.

6. In a door operating mechanism, a trackway having upper and lower runs each provided at one end with a pivoted run section, a door operating mechanism, blocks movable along the track in said upper and lower runs thereof, means operatively connecting the blocks with the door operating mechanism, said pivoted run sections being depressible by the weight of the blocks thereon for releasably securing the blocks against movement, and means for elevating the pivoted run sections to release the blocks to permit movement of the door to either open or closed position.

7. In a door operating mechanism, a trackway having upper and lower runs each provided at one end with a pivoted run section, a door operating mechanism, blocks movable along the track in said upper and lower runs thereof, means operatively connecting the blocks with the door operating mechanism, said pivoted run sections being depressible by the weight of the blocks thereon for releasably securing the blocks against movement, and means for elevating the pivoted run sections to release the blocks to permit movement of the doors to either open or closed position, said means including a pivoted link, means pivotally connecting said link with the pivoted run sections, and means for swinging said link about its pivot to elevate the pivoted run sections.

8. A door operating mechanism including a triangular arrangement of pulleys, a door opening cable windable on one of the pulleys and connected at one end with the door, a door closing cable windable on a second one of the pulleys and connected at one end with the door, rack and pinion means connecting the first and third pulleys for transmitting movement from one to the other of said first and third pulleys, a trackway provided with upper and lower runs, a pair of blocks operating in the upper run of said trackway, a cable on the third pulley and connected with one of said blocks, a weight equipped take-up cable connected at one end with the other of said blocks, a second pair of blocks operating in the lower runway of said track, said door closing cable having one end connected with one of the second blocks, a weight equipped take-up cable connected with the other of said second blocks, and means engageable with said blocks for moving them along the trackway, movement of the first mentioned pair of blocks in one direction operating to open the door, and movement of the second pair of blocks in one direction operating to close the door.

9. A door operating mechanism including a triangular arrangement of pulleys, a door opening cable windable on one of the pulleys and connected at one end with the door, a door closing cable windable on a second one of the pulleys and connected at one end with the door, rack and pinion means connecting the first and third pulleys for transmitting movement from one to the other of said first and third pulleys, a trackway provided with upper and lower runs, a pair of blocks operating in the upper run of said trackway, a cable on the third pulley and connected with one of said blocks, a weight equipped take-up cable connected at one end with the other of said blocks, a second pair of blocks operating in the lower runway of said track, said door closing cable having one end connected with one of the second blocks, a weight equipped take-up cable connected with the other of said second blocks, and means engageable with said blocks for moving them along the trackway, movement of the first mentioned pair of blocks in one direction operating to open the door, and movement of the second pair of blocks in one direction operating to close the door.

10. A door operating mechanism including a triangular arrangement of pulleys, a door opening cable windable on one of the pulleys and connected at one end with the door, a door closing cable windable on a second one of the pulleys and connected at one end with the door, rack and pinion means connecting the first and third pulleys for transmitting movement from one to the other of said first and third pulleys, a trackway provided with upper and lower runs, a pair of blocks operating in the upper run of said trackway, a cable on the third pulley and connected with one of said blocks, a weight equipped take-up cable connected at one end with the other of said blocks, a second pair of blocks operating in the lower runway of said track, said door closing cable having one end connected with one of the second blocks, a weight equipped take-up cable connected with the other of said second blocks, and means engageable with said blocks for moving them along the trackway, movement of the first mentioned pair of blocks in one direction operating to open the door, and movement of the second pair of blocks in one direction operating to close the door.

nected at one with the door, a door closing cable windable on a second one of the pulleys and connected at one end with the door, rack and pinion means connecting the first and third pulleys for transmitting movement from one to the other of said first and third pulleys, a trackway provided with upper and lower runs, a pair of blocks operating in the upper run of said trackway, a cable on the third pulley and connected with one of said blocks, a weight equipped take-up cable connected at one end with the other of said blocks, a second pair of blocks operating in the lower runway of said track, said door closing

cable having one end connected with one of the second blocks, a weight equipped take-up cable connected with the other of said second blocks, and means engageable with said blocks for moving them along the trackway, movement of the first mentioned pair of blocks in one direction operating to open the door, and movement of the second pair of blocks in one direction operating to close the door, and means for engaging the blocks with the ends of their respective runways for locking the doors, and means for simultaneously releasing all of the blocks. 5 10

CHESTER A. DILLER.
